AMPLIFIER OF THE MAGNETRON TYPE

William C. Brown, Lincoln, Mass., assignor to
Raytheon Manufacturing Company, Newton,
Mass., a corporation of Delaware

Application April 9, 1945, Serial No. 587,249

13 Claims. (Cl. 315—39)

1

My present invention relates to electron-discharge devices, and more particularly to electron-discharge devices for amplifying electrical oscillations having a wave length, for example, of the order of a few centimeters, or less.

One of the objects of my present invention is to provide an electron-discharge device of the general character indicated which is capable of handling extremely high-frequency energy at high power levels.

Another object of my present invention is to provide an electron-discharge device having great sensitivity.

These, and other objects of my present invention, which will become more apparent as the detailed description thereof progresses, are attained, briefly, in the following manner:

The electron-discharge device of my present invention is of the so-called magnetron type. It comprises, in general, a cathode structure, an anode structure, and means for establishing a magnetic field in a direction perpendicular to the electron-path between said cathode and anode structures.

Said anode structure, preferably, includes what I shall designate as primary and secondary cavity resonators, and while not necessary, I prefer that at least one of said cavity resonators comprise a plurality of anode members, each pair of adjacent anode members, together with that portion of the anode structure lying therebetween, constituting a resonant line.

In addition to the magnetic field already referred to, I provide the device with such electric fields, coacting with each other and with said magnetic field, that the electrons emitted by the cathode are initially substantially uniformly distributed in a stream having an at least partially annular, cylindrical configuration, said coacting magnetic and electric fields also causing said stream simultaneously to rotate on its own axis, and drift along the same past the above-described cavity resonators.

I further provide the device with means for introducing high-frequency energy into the primary cavity resonator, to excite the same and correspondingly velocity modulate the electron-stream as said stream passes said resonator.

As a result of said modulation, said stream, in passing the secondary cavity resonator, causes the latter to be excited into oscillation, and the high-frequency energy generated therein may be extracted therefrom.

Now, the primary cavity resonator may be considered a signal wave transmission network

2

functioning as a "buncher," and the secondary cavity resonator, a similar network functioning as a "catcher," so that when energy is introduced into the primary cavity resonator at a low power level, the velocity modulation of the electron-stream, brought about as above described, causes said energy to be amplified in the secondary cavity resonator.

I have found that an electron-discharge device so made is capable of handling extremely high-frequency energy at high power levels, and that such a device is considerably more sensitive than devices heretofore made for similar purposes.

In the accompanying specification I shall describe, and in the annexed drawings show, an illustrative embodiment of the electron-discharge device of my present invention. It is, however, to be clearly understood that I do not wish to be limited to the details herein shown and described for purposes of illustration only, inasmuch as changes therein may be made without the exercise of invention and within the true spirit and scope of the claims hereto appended.

In said drawings, Fig. 1 is a longitudinal sectional view taken substantially through the center of an electron-discharge device made in accordance with the principles of my present invention; and

Fig. 2 is a transverse sectional view taken along line 2—2 of Fig. 1.

Referring now more in detail to the aforesaid illustrative embodiment of my present invention, and with particular reference to the drawings illustrating the same, the numeral 5 generally designates an electron-discharge device of the so-called magnetron type. Said device comprises, in general, an anode structure 6, a cathode structure 7, magnetic means 8 for establishing a magnetic field in a direction perpendicular to the electron path between said cathode and anode structures, and tuning means 9.

In the device shown, the anode structure 6 includes a pair of axially aligned, abutting, cylindrical bodies 10 and 11, made of highly conductive material, such as copper, and hermetically sealed at their adjacent ends, as at 12. Said bodies are provided, respectively, with a multiplicity, here shown as eight, of anode members, preferably, in the form of interiorly-extending, radially-disposed vanes 13 and 14, each pair of adjacent vanes, together with that portion of the corresponding cylindrical body 10 or 11 lying therebetween, constituting a section of a wave transmission network, more particularly, a resonant line whose natural resonant frequency is, as is

well known in the art to which my present invention relates, a function of the geometry of the physical elements making up the same. I shall further describe the anode members 13 and 14 when referring, in a later portion of this specification, to the details of the tuning means 9.

The anode structure 6 is closed at its outer ends, for example, by end plates 15 and 16, with the respective junctions between the cylindrical bodies 10 and 11, and said plates 15 and 16, hermetically sealed, as at 17 and 18. At the meeting ends of the cylindrical bodies 10 and 11, the anode structure is provided with a centrally-apertured disk 19, which acts as a shield to divide said anode structure into, what I shall call, primary and secondary cavity resonators 14' and 13', the former including the anode members 14 and the latter including the anode members 13, said shield preventing coupling between said resonators.

The disk 19 has a short cylindrical section 20 secured in the central aperture thereof to provide an annular passage, about the cathode structure 7, between said primary and secondary cavity resonators.

The cathode structure 7, which is coaxial with the anode structure 6, includes a cathode sleeve 21, conventionally made of nickel, or the like, provided with a reduced portion 22 extending from about the lower edges of the anode members 14 to a point corresponding to about one-third of the distance between the lower and upper edges of the anode members 13, measured from said lower edges. Said reduced portion 22 is, in turn, provided with a reduced portion 23 whose length, preferably, is a small fraction of the width of the anode members 14 and whose upper end, preferably, is on a line with the upper edges of said anode members 14, said reduced portion 23 being provided with a highly electron-emissive coating 24, for example, of the well known alkaline-earth metal oxide type.

In order properly to support the cathode structure 7 with respect to the anode structure 6, the sleeve 21 thereof may be reduced, as at 25, to fit into an elongated, electrically-conductive tubular member 26 having, at its outer end, a ferrule 27 closed by a glass seal 28. Said seal, together with one or more glass beads 29 disposed within the tubular member 26, supports a lead-in conductor 30, which passes through said member 26 and has its upper end connected, as at 31, to one terminal of a cathode-heating filament 32. The other terminal of said filament may be connected, as at 33, to the cathode sleeve 21.

In order to convey current to the filament 32, the lead-in conductor 30 is connected by a conductor 34 to one terminal of a suitable source of E. M. F. (not shown), the other terminal of said source of E. M. F. being connected by a conductor 35 to a heat-dissipating member 36 fixed upon the lower end of the tubular member 26.

In order properly to insulate the cathode structure 7 from the anode structure 6, the tubular member 26 may have fixed thereto a cup-like bushing 37 sealed into one end of a glass tube 38, the other end of said glass tube having sealed therein a tubular bushing 39, in turn, secured to a tubular pole piece 40, constituting one of the components of the magnetic means 8.

Said pole piece 40 may be hermetically sealed, as at 41, into the end plate 16, and be provided with a central bore 42 whereby the cathode structure 7 may enter the device.

Another tubular pole piece 43 may be hermetically sealed, as at 44, into the end plate 15, said pole piece and the pole piece 40 being fixed, for example, to the opposite ends of a horseshoe magnet (not shown), whereby an appropriate magnetic field may be established, as previously indicated, in a direction perpendicular to the electron-path between the cathode structure 7 and anode structure 6.

If in a device as thus far described, the cathode structure 7 is suitably heated, and the anode structure 6 is made appropriately positive with respect to said cathode structure, for example, by means of a source 45 of E. M. F., electrical oscillations may be generated in the primary cavity resonator 14', said oscillations having a wave length determined, primarily, by the distributed capacitance and inductance built into said resonator as a function of the geometry thereof, and more especially of the dimensions of the elements making up the resonant lines above referred to.

However, for the purposes of my present invention, such oscillations are undesirable, and in order to prevent them, I provide means for driving the electrons, emitted by the coating 24, away from the vicinity of the anode members 14 as soon after such emission as possible. To this end, I provide, for example, a short, cylindrical, repelling electrode 46, adapted to be supported, in the space between the reduced portion 22 of the cathode structure and the anode members 14, at the end of a lead-in conductor 47, the latter passing out of the device and being supported in a glass seal 48, fused into a pipe 49 which is threaded and hermetically sealed into the end plate 16. The repelling electrode 46 is made appropriately negative with respect to the cathode structure 7, for example, by means of a suitable source 50 of E. M. F.

By the means just described, the electrons emitted by the cathode are urged out of the primary resonator 14', through the passage presented between said cathode and the cylindrical section 20, and into the secondary cavity resonator 13'.

However, for the purposes of my present invention, it may not be desirable that such electrons be captured by the anode members 13 of said secondary cavity resonator. Therefore, I provide, for example, a short, cylindrical, collecting electrode 51, adapted to be supported, adjacent the upper end of the cathode structure 7, and spaced from the inner ends of the anode members 13, by a lead-in conductor 52, said lead-in conductor passing out of the device and being supported in a glass seal 53, fused into a pipe 54 which is threaded and hermetically sealed into the cylindrical body 10. The collecting electrode 51 is made appropriately positive with respect to the anode structure 6, by means, for example, of a suitable source 55 of E. M. F.

Now it will be noted that by means of the pole pieces 43 and 40, a magnetic field is established in a direction perpendicular to the electron-path between the cathode structure 7 and the anode members 14 of the primary cavity resonator 14'. It will further be noted that an electric field is established between the cathode structure 7 and the anode structure 6; another electric field is established between the cathode structure 7 and the repelling electrode 46; and still another electric field is established between the anode structure 6 and the collecting electrode 51.

These various fields extend in such directions, and are adjusted to be of such relative intensities,

that they coact to initially substantially uniformly distribute the electrons emitted by the cathode in an at least partially annular, cylindrical stream, and to cause said stream simultaneously to rotate on its own axis, and drift axially past the anode members 14 and 13 of the cavity resonators 14' and 13'.

Because, as already indicated, the electrons emitted by the cathode are rapidly repelled from the vicinity of the primary cavity resonator 14', said resonator is not excited by the electron-stream fashioned as above, and because said stream is rapidly gathered in by the collecting electrode 51 and not permitted to be captured by or linger in the vicinity of the secondary cavity resonator 13', the latter is, likewise, not excited by said stream.

However, I now provide a loop 56, which extends into the space defined by any two of the anode members 14 of the primary cavity resonator 14', said loop being connected to a conductor 57 entering the device through a glass seal 58, fused into a pipe 59 which is threaded and hermetically sealed into the cylindrical body 11, and when high-frequency energy is applied to the loop 56, said primary cavity resonator 14' is excited into oscillation.

Now, as the electron-stream, fashioned as above described, passes the elements making up the primary cavity resonator 14', some of the electrons are accelerated and others are retarded, whereby said stream becomes velocity modulated in accordance with the high-frequency energy fed into the device; and as said stream drifts past the elements making up the secondary cavity resonator 13', it delivers energy to said secondary cavity resonator and, accordingly, excites the same into amplified oscillations.

In order to extract power from the device, I may, for example, introduce a loop 60 into the space defined by any two of the anode members 13 of the secondary cavity resonator 13', said loop being connected to a conductor 61 supported in a glass seal (not shown), fused into a pipe 62 which is threaded and hermetically sealed into the cylindrical body 10.

In order to assure the efficient absorption of energy from the velocity modulated electron-stream, I prefer that the secondary cavity resonator 13' be tunable, and to this end, I proceed as follows:

Each anode member 13 of said secondary cavity resonator may be provided, preferably, in both its upper and lower edges, adjacent its inner end, with cut-away portions or slots 63, said slots being receptive of two pairs of concentric conducting straps 64 and 65, and 66 and 67, the straps of each pair thereof alternately contacting successive anode members 13. Said straps present therebetween capacitances entering into the determination of the natural resonant frequency of the secondary cavity resonator 13'.

While not necessary, in a similar manner, each anode member 14 of the primary cavity resonator 14' may be slotted, as at 68, and provided with two pairs of straps 69 and 70, and 71 and 72, said straps presenting therebetween capacitances entering into the determination of the natural resonant frequency of said primary cavity resonator 14'.

Inasmuch as the straps of each pair thereof have a capacitance therebetween, they may be considered the plates of a capacitor, and by varying the capacitance between at least one of said pairs, and introducing additional capacitance in

parallel therewith, the device can be tuned, and this may be accomplished as follows:

As stated, I prefer to apply the tuning means to the secondary cavity resonator 13' alone, altering the frequency thereof until said frequency matches the frequency at which the primary cavity resonator is oscillating, and, therefore, the frequency of the velocity modulation of the electron-stream, thereby assuring maximum absorption of energy from said electron-stream.

A plunger 73, made of highly conductive material, such as copper, is slidably mounted in the bore 14 of the tubular pole piece 43, the inner end of said plunger being cupped to provide a conducting annulus 75 which, when moved, for example, intermediate the straps 64 and 75, constitutes, together with said straps, a variable capacitor. In order to permit the conductor 52, which supports the collecting electrode 51 at its inner end, to pass out of the device, the annulus 75 may be provided with an elongated slot 76, and in order to maintain the device air-tight, I provide an apertured flexible diaphragm 77, hermetically sealed, at its periphery 78, to the cylindrical body 10 of the anode structure 6, and similarly sealed, at its central aperture 79, to said plunger 73.

The introduction of the annulus 75 into the space between the straps 64 and 65 does two things. First, it reduces the effective area of the surfaces of said straps between which the above-mentioned capacitance exists, but inasmuch as this capacitance is small to begin with, the overall effect on the frequency of the secondary cavity resonator 13' is, likewise, small. Second, it forms, together with said straps, two capacitors connected in series, which did not, before, exist. Inasmuch as the gaps between said annulus and said straps are small, the total capacitance of the newly formed capacitors is relatively large, and this capacitance, added in parallel with what remains of the original capacitance, has a considerable effect upon the frequency of the secondary cavity resonator. Hence, even if there is considerable deviation between the natural resonant frequency of the secondary cavity resonator and the frequency of the oscillating energy in the primary cavity resonator, which oscillating energy it is desired to amplify, the frequency of the secondary cavity resonator can be adjusted by the means described to assure the most efficient absorption of energy from the velocity modulated electron-stream.

There remains to be described the control mechanism of the tuning means 9, by means of which the penetration of the annulus 75 into the space intermediate the straps 64 and 65 may be varied.

While not limited thereto, I prefer to construct such tuning control means as follows:

Secured on the upper end of the plunger 73 is a threaded bushing 80, engageable in a disk 81 whose periphery may be provided with a V-cut 82, constituting a ball-bearing race. Surrounding said race is another race comprised of two cooperating bevelled rings 83 and 84, the ring 83 being carried by a disk 85, and the ring 84 being pressed into cooperation with said ring 83 by an annular spring 86. The races are receptive therebetween of bearing balls 87, and the spring 86 is affixed to the disk 85 by a flat retaining ring 88 and bolts 89.

The disk 85 is maintained against rotation by being bolted, as at 90, to a plate 91 fixed, at its center, to the pole piece 43, the plate 91 being

provided with bearings (not shown) in which is journalled a shaft 92. Mounted upon the shaft 92 is a worm gear 93 engageable with a worm wheel 94 secured to the disk 81 by means of bolts 95. The shaft 92 is provided, at one end, with a pinion 96, whereby the same may be manually or otherwise rotated, slidably to move the plunger 13 with respect to the pole piece 43, and thus vary the capacitances between the straps 64 and 65, and the annulus 75 and said straps.

This completes the description of the aforesaid illustrative embodiment of my present invention. It will be noted from all of the foregoing that I have provided an electron-discharge device of the magnetron type which is extremely sensitive and, therefore, capable of responding to a low-intensity input, and greatly amplifying the same. It will also be noted that the electron-discharge device of my present invention is capable of handling extremely high-frequency energy at high power levels.

Other advantages of my present invention will readily occur to those skilled in the art to which the same relates.

What is claimed is:

1. An electron-discharge device comprising: a cathode; an anode structure, spaced from said cathode, and including a pair of cavity resonators; said cathode and said anode structure being adapted to have an electric field established therebetween; means, adjacent said cathode and said anode structure, adapted to establish a magnetic field therebetween perpendicular to and cooperable with said electric field, thereby to distribute electrons emitted by said cathode substantially uniformly in a rotating, annular stream; means, adjacent said cathode and said anode structure, adapted to establish an electric field substantially parallel to said magnetic field and substantially perpendicular to said first-named electric field, thereby to cause said electron stream to drift axially past said cavity resonators; means, coupled to one of said cavity resonators, adapted to introduce high-frequency energy therein, whereby as said electron stream drifts past the same, it is accordingly velocity modulated, and as the velocity-modulated electron stream drifts past the other of said cavity resonators, the latter is thereby excited into oscillation; and means, coupled to said last-named cavity resonator, adapted to extract therefrom the high-frequency energy generated therein.

2. An electron-discharge device comprising: a cathode; an anode structure, spaced from said cathode, and including a pair of cavity resonators each of which comprises a pair of radially disposed anode members together with that portion of said anode structure lying therebetween; said cathode and said anode structure being adapted to have an electric field established therebetween; means, adjacent said cathode and said anode structure, adapted to establish a magnetic field therebetween perpendicular to and cooperable with said electric field, thereby to distribute electrons emitted by said cathode substantially uniformly in a rotating, annular stream; means, adjacent said cathode and said anode structure, adapted to establish an electric field substantially parallel to said magnetic field and substantially perpendicular to said first-named electric field, thereby to cause said electron stream to drift axially past said cavity resonators; means, coupled to one of said cavity resonators, adapted to introduce high-frequency energy therein, whereby as said electron stream drifts past the same, it is accordingly velocity modulated, and as the velocity-modulated electron stream drifts past the other of said cavity resonators, the latter is thereby excited into oscillation; and means, coupled to said last-named cavity resonator, adapted to extract therefrom the high-frequency energy generated therein.

3. An electron-discharge device comprising: a cathode; an anode structure, spaced from said cathode, and including a pair of cavity resonators; said cathode and said anode structure being adapted to have an electric field established therebetween; means, adjacent said cathode and said anode structure, adapted to establish a magnetic field therebetween perpendicular to and cooperable with said electric field, thereby to distribute electrons emitted by said cathode substantially uniformly in a rotating, annular stream; means, adjacent said cathode and said anode structure, adapted to establish an electric field substantially parallel to said magnetic field and substantially perpendicular to said first-named electric field, thereby to cause said electron stream to drift axially past said cavity resonators; means, coupled to one of said cavity resonators, adapted to introduce high-frequency energy therein, whereby as said electron stream drifts past the same, it is accordingly velocity modulated, and as the velocity-modulated electron stream drifts past the other of said cavity resonators, the latter is thereby excited into oscillation; and means, coupled to said last-named cavity resonator, adapted to extract therefrom the high-frequency energy generated therein.

4. An electron-discharge device comprising: a cathode; an anode structure, spaced from said cathode, and including a pair of cavity resonators each of which comprises a pair of radially disposed anode members together with that portion of said anode structure lying therebetween; said cathode and said anode structure being adapted to have an electric field established therebetween; means, adjacent said cathode and said anode structure, adapted to establish a magnetic field therebetween perpendicular to and cooperable with said electric field, thereby to distribute electrons emitted by said cathode substantially uniformly in a rotating, annular stream; means, adjacent said cathode and said anode structure, adapted to establish an electric field substantially parallel to said magnetic field and substantially perpendicular to said first-named electric field, thereby to cause said electron stream to drift axially past said cavity resonators; means, coupled to one of said cavity resonators, adapted to introduce high-frequency energy therein, whereby as said electron stream drifts past the same, it is accordingly velocity modulated, and as the velocity-modulated electron stream drifts past the other of said cavity resonators, the latter is thereby excited into oscillation; and means, coupled to said last-named cavity resonator, adapted to extract therefrom the high-frequency energy generated therein.

5. An electron-discharge device comprising: a cathode; an anode structure, spaced from said cathode, and including a pair of cavity resonators

each of which comprises a pair of radially disposed anode members together with that portion of said anode structure lying therebetween; said cathode and said anode structure being adapted to have an electric field established therebetween; means, adjacent said cathode and said anode structure, adapted to establish a magnetic field therebetween perpendicular to and cooperable with said electric field, thereby to distribute electrons emitted by said cathode substantially uniformly in a rotating, annular stream; means, adjacent said cathode and said anode structure, adapted to establish an electric field substantially parallel to said magnetic field and substantially perpendicular to said first-named electric field, thereby to cause said electron stream to drift axially past said cavity resonators; means, coupled to one of said cavity resonators, adapted to introduce high-frequency energy therein, whereby as said electron stream drifts past the same, it is accordingly velocity modulated, and as the velocity-modulated electron stream drifts past the other of said cavity resonators, the latter is thereby excited into oscillation; a pair of conducting straps alternately contacting the successive anode members of said last-named cavity resonator; a conducting member, supported adjacent said last-named cavity resonator and movable with respect to said conducting straps, adapted to tune said last-named cavity resonator to the frequency of said velocity modulation; and means, coupled to said last-named cavity resonator, adapted to extract therefrom the high-frequency energy generated therein.

6. An electron-discharge device comprising: a cathode; an anode structure, spaced from said cathode, and including primary and secondary cavity resonators; said cathode and said anode structure being adapted to have an electric field established therebetween; means, adjacent said cathode and said anode structure, adapted to establish a magnetic field therebetween, perpendicular to and cooperable with said electric field, thereby to distribute electrons emitted by said cathode substantially uniformly in a rotating, annular stream; a repeller electrode, supported adjacent said primary cavity resonator, and adapted to establish an electric field substantially parallel to said magnetic field and substantially perpendicular to said first-named electric field, thereby to cause said electron stream to drift axially past said primary and secondary cavity resonators; means, coupled to said primary cavity resonator, adapted to introduce high-frequency energy therein, whereby as said electron stream drifts past the same, it is accordingly velocity modulated, and as the velocity-modulated electron stream drifts past the said secondary cavity resonator, the latter is thereby excited into oscillation; a collecting electrode, supported adjacent said secondary cavity resonator, and adapted to establish an electric field between itself and said anode structure, thereby to collect the electrons drifting past said secondary cavity resonator, and means, coupled to said secondary cavity resonator, adapted to extract therefrom the high-frequency energy generated therein.

7. An electron-discharge device comprising: a cathode; an anode structure, spaced from said cathode, and including primary and secondary cavity resonators each of which comprises a pair of radially disposed anode members together with that portion of said anode structure lying therebetween; said cathode and said anode structure

being adapted to have an electric field established therebetween; means, adjacent said cathode and said anode structure, adapted to establish a magnetic field therebetween, perpendicular to and cooperable with said electric field, thereby to distribute electrons emitted by said cathode substantially uniformly in a rotating, annular stream; a repeller electrode, supported adjacent said primary cavity resonator, and adapted to establish an electric field substantially parallel to said magnetic field and substantially perpendicular to said first-named electric field, thereby to cause said electron stream to drift axially past said primary and secondary cavity resonators; means, coupled to said primary cavity resonator, adapted to introduce high-frequency energy therein, whereby as said electron stream drifts past the same, it is accordingly velocity modulated, and as the velocity-modulated electron stream drifts past said secondary cavity resonator, the latter is thereby excited into oscillation; a collecting electrode, supported adjacent said secondary cavity resonator, and adapted to establish an electric field between itself and said anode structure, thereby to collect the electrons drifting past said secondary cavity resonator; and means, coupled to said secondary cavity resonator, adapted to extract therefrom the high-frequency energy generated therein.

8. An electron-discharge device comprising: a cathode; an anode structure, spaced from said cathode, and including primary and secondary cavity resonators; said cathode and said anode structure being adapted to have an electric field established therebetween; means, adjacent said cathode and said anode structure, adapted to establish a magnetic field therebetween, perpendicular to and cooperable with said electric field, thereby to distribute electrons emitted by said cathode substantially uniformly in a rotating, annular stream; a repeller electrode, supported adjacent said primary cavity resonator, and adapted to establish an electric field substantially parallel to said magnetic field and substantially perpendicular to said first-named electric field, thereby to cause said electron stream to drift axially past said primary and secondary cavity resonators; means, coupled to said primary cavity resonator, adapted to introduce high-frequency energy therein, whereby as said electron stream drifts past the same, it is accordingly velocity modulated, and as the velocity-modulated electron stream drifts past said secondary cavity resonator, the latter is thereby excited into oscillation; a collecting electrode, supported adjacent said secondary cavity resonator, and adapted to establish an electric field between itself and said anode structure, thereby to collect the electrons drifting past said secondary cavity resonator; means, supported adjacent said secondary cavity resonator and movable with respect thereto, adapted to tune the same to the frequency of said velocity modulation; and means, coupled to said secondary cavity resonator, adapted to extract therefrom the high-frequency energy generated therein.

9. An electron-discharge device comprising: a cathode; an anode structure, spaced from said cathode, and including primary and secondary cavity resonators each of which comprises a pair of radially disposed anode members together with that portion of said anode structure lying therebetween; said cathode and said anode structure being adapted to have an electric field established therebetween; means, adjacent said

11

cathode and said anode structure, adapted to establish a magnetic field therebetween, perpendicular to and cooperable with said electric field, thereby to distribute electrons emitted by said cathode substantially uniformly in a rotating, annular stream; a repeller electrode, supported adjacent said primary cavity resonator, and adapted to establish an electric field substantially parallel to said magnetic field and substantially perpendicular to said first-named electric field, thereby to cause said electron stream to drift axially past said primary and secondary cavity resonators; means, coupled to said primary cavity resonator, adapted to introduce high-frequency energy therein, whereby as said electron stream drifts past the same, it is accordingly velocity modulated, and as the velocity-modulated electron stream drifts past said secondary cavity resonator, the latter is thereby excited into oscillation; a collecting electrode, supported adjacent said secondary cavity resonator, and adapted to establish an electric field between itself and said anode structure, thereby to collect the electrons drifting past said secondary cavity resonator; means, supported adjacent said secondary cavity resonator and movable with respect thereto, adapted to tune the same to the frequency of said velocity modulation; and means, coupled to said secondary cavity resonator, adapted to extract therefrom the high-frequency energy generated therein.

10. An electron-discharge device comprising: a cathode; an anode structure, spaced from said cathode, and including primary and secondary cavity resonators each of which comprises a pair of radially disposed anode members together with that portion of said anode structure lying therebetween; said cathode and said anode structure being adapted to have an electric field established therebetween; means, adjacent said cathode and said anode structure, adapted to establish a magnetic field therebetween, perpendicular to and cooperable with said electric field, thereby to distribute electrons emitted by said cathode substantially uniformly in a rotating, annular stream; a repeller electrode, supported adjacent said primary cavity resonator, and adapted to establish an electric field substantially parallel to said magnetic field and substantially perpendicular to said first-named electric field, thereby to cause said electron stream to drift axially past said primary and secondary cavity resonators; means, coupled to said primary cavity resonator, adapted to introduce high-frequency energy therein, whereby as said electron stream drifts past the same, it is accordingly velocity modulated, and as the velocity-modulated electron stream drifts past said secondary cavity resonator, the latter is thereby excited into oscillation; a collecting electrode, supported adjacent said secondary cavity resonator, and adapted to establish an electric

12

field between itself and said anode structure, thereby to collect the electrons drifting past said secondary cavity resonator; a pair of conducting straps alternately contacting the successive anode members of said secondary cavity resonator; a conducting member, supported adjacent said secondary cavity resonator and movable with respect to said conducting straps, adapted to tune said secondary cavity resonator to the frequency of said velocity modulation; and means, coupled to said secondary cavity resonator, adapted to extract therefrom the high-frequency energy generated therein.

11. An electron-discharge device comprising: 15 an anode structure; a cathode having an effective electron emitting surface, spaced from said anode; means for establishing an electric field between said cathode and said anode; said anode comprising at least one signal wave transmission network, and having signal input and output means cooperating therewith; and means for establishing magnetic flux lines parallel to said emitting surface of said cathode.

12. An electron-discharge device comprising: 20 an anode structure; a cathode having an effective electron emitting surface, spaced from said anode; means for establishing an electric field between said cathode and said anode; said anode comprising at least one signal wave transmission network, and having signal input and output means cooperating therewith; and means for establishing magnetic flux lines parallel to said emitting surface of said cathode.

13. An electron-discharge device comprising: 25 an anode structure; a cathode having an effective electron emitting surface, spaced from said anode, said cathode being exposed to fields set up by high frequency energy supplied to said anode structure; means for establishing an electric field between said cathode and said anode; said anode comprising at least one signal wave transmission network, and having signal input and output means cooperating therewith; and means for establishing magnetic flux lines parallel to said emitting surface of said cathode.
